E. SCHRÖDER
ELECTRIC HEATING MACHINE

Filed Dec. 28, 1922

Fig. 2.

INVENTOR

Edmund Schröder.

*By William C. Linton
Atty.*

UNITED STATES PATENT OFFICE.

EDMUND SCHRÖDER, OF BERLIN, GERMANY, ASSIGNOR TO THE FIRM BRAUN-BRÜNING & CO., OF BASEL, SWITZERLAND.

ELECTRIC HEATING MACHINE.

Application filed December 28, 1922. Serial No. 609,518.

To all whom it may concern:

Be it known that I, EDMUND SCHRÖDER, a citizen of the German Republic, residing at Berlin, in the Republic of Germany, have 5 invented a certain new and useful Improvement in Electric Heating Machines; and I do hereby declare that the following is a full, clear, and exact description of the invention, such as will enable others skilled 10 in the art to which it appertains to make and use the same.

This invention relates in general to electric heating devices and in particular to the clamping means of the same. The present 15 invention relates especially to such clamping devices as described and shown in my pending United States application Serial- Number 482740, which relates to a device for heating forging pieces by electric re- 20 sistance heating.

My invention is illustrated, by means of example, in the accompanying drawing, in which Figure 1 is a perspective illustration of the improved clamping device, and Figure 2 is a similar illustration showing a 25 modified form of construction.

c c (Fig. 1) are horizontal extensions of the poles *c² d²* of the electric apparatus, upon which are arranged sleeves encompassing 30 the pole extensions like clips and having each a cylindrical extension *z*. These latter extensions are bipartite, as shown, and each of their gaps *s* communicates with the slot of the respective sleeve.

The extensions *z* serve as supports for the clamping devices proper, of which one is shown in the right-hand half of Figure 1. This device (as well as the other one not shown) consists of a lower clamping member *a* and of an upper clamping member *b* which is displaceable upon a guide member *j²* upon which it may be displaced by a threaded spindle *j¹*. The guide member *j²* forms at its lower end a sleeve *j³* which encompasses the extension *z* of the sleeve *u*. It is obvious that by clamping fast a work piece between the clamping members *a* and *b* the sleeve *y* is clamped fast upon the pole extension *c*, because the halves of the sleeve 45 extension *z* are pressed one against the other whereby the width of the slot of the sleeve is appropriately narrowed, this sleeve being, thus, firmly clamped to the extension *c*.

The halves of the sleeve extension *z* may

be connected with each other by a screw, 55 preferably with a counter-sunk head (not shown), located in front of the clamping member *a* and serving to press the sleeve *y* fast upon the pole-extension *c* independently of the clamping member *b*. 60

It is obvious that with this arrangement the clamping devices may not only be turned in a vertical plane upon the pole extensions *c*, and may be horizontally displaced upon them, but each pair of clamping cheeks (*a* 65 and *b*) may be turned in a vertical plane (standing at right angles to the just-mentioned vertical plane) upon the sleeve extensions *z* and may be horizontally displaced upon them (at right angles to the sleeves 70 *y*). The shiftability and adjustability of the clamping cheeks is, thus, considerably enhanced.

The clamping devices (*a j³ j² b*) may be drawn off the extensions *z* without special 75 disconnections and may be replaced in the easiest manner by other clamping devices, or clamping cheeks respectively.

The shiftability and adjustability may be still more improved by making the pole 80 extensions *c* horizontally movable in the manner shown in Figure 2, in which each extension is provided at its inner end (where it is to be attached to the pole) with a pivot *w* adapted to turn in a clip *v* attached to the respective pole. This arrangement is, it is true, applicable only in cases where the length of the extensions *c* is so limited that providing special supports for 85 their outer ends may be dispensed with. 90 But as regards apparatus of comparatively small dimensions, the increased shiftability increases also the usefulness of the device, especially where the lengths of material to be electrically heated 95 are comparatively short.

Having now described my invention, what I desire to secure by a patent of the United States is:

1. The combination with an electric heating machine having pole extensions and work clamping members, of means for connecting said work clamping members to said pole extensions, said connecting means each comprising a sleeve adapted to encircle 100 a pole extension, and a cylindrical extension 105 formed with each sleeve supporting said work clamping members whereby when

work is retained between said clamping members said sleeves will be locked to said pole extensions.

2. The combination with an electric heating machine having a pole extension, a sleeve encircling said extension, a cylindrical extension formed with said sleeve, said cylindrical extension consisting of two bifurcated members, and a pair of work clamping

members arranged about said cylindrical extension whereby when work is retained between said clamping members said bifurcated members will be forced together and said sleeve retained against movement upon said pole extension.

In witness whereof I have hereunto set my hand.

EDMUND SCHRÖDER.
